MANIFOLDING ATTACHMENT FOR WRIT-
ING MACHINES

Hans Ziegler, Zelliken-Zurich, Switzerland

Application January 23, 1936, Serial No. 60,424
In Switzerland March 28, 1935

3 Claims. (Cl. 197—126)

Several designs of appliances or devices on typewriters for making copies by means of auxiliary ribbons are known to-day. The latter thus either are stretched onto a frame mounted on the typewriter-platen and fastened thereto by special means or stretched between two levers mounted on the platen-carriage and folded forward for use. Both types of such devices show great disadvantages. With the first kind the frames must fit exactly onto the platen, i. e. a great number of different frames must be provided for all the different models of typewriters. It furthermore is very difficult, in the case of various models of typewriters, to hold said frames fast onto the platen, lest the one or the other function of the typewriter be impaired. The devices of the second kind mentioned cannot be applied to all models of typewriters, since in the case of the latter being equipped with a sheet-holder which is set at an angle relative to the platen or curved in plan we do not succeed in slipping the auxiliary ribbon under said sheet-holder when folding the levers downward. Said devices moreover require quite some space so that their application for portable typewriters is questioned. The auxiliary ribbon furthermore cannot be stretched sufficiently tight between the levers which are of quite some length and the paper thus is liable to become smudged.

All of said devices and appliances yet show a further material disadvantage: exchanging of the auxiliary ribbons and their fastening with a suitable tension offer great difficulties and often lead to a soiling of our hands or a smudging of the paper.

Said disadvantages are eliminated by way of the present invention.

The object of the invention at hand is a device on typewriters for making copies by means of auxiliary ribbons, whereby a rod is mounted longitudinally on the platen carriage, at least one support being plugged onto said rod, another pair of rods mounted parallel to the first-mentioned rod and revolvably onto the lateral members of said first rod and being joined in the center by a hollow rod, said hollow rod containing a helical spring pushing said pair of rods away from each other, said pair of rods being individually axially movable within limits of stopping means inside of said hollow rod and carrying each at its outer end a curved arm corresponding to the curvature of the platen, the free end of said arm being adapted for receiving an auxiliary ribbon provided with end-pieces.

The device according to this invention can be

applied for all models of typewriters. Due to its flexibility we succeed in any and all cases in bringing the auxiliary ribbon readily and easily between the sheets of paper and underneath the sheet-holder and the lifting device for the typewriter-ribbon. The auxiliary ribbon always is stretched as desired so that a smudging of the paper is excluded.

In the accompanying drawing a device according to the present invention is exemplified, 10 where—

Fig. 1 is a front-elevation of the appliance in place and where a single auxiliary ribbon is used;

Fig. 2 is a front-elevation of the device according to Fig. 1 in which, however, a second auxiliary 15 ribbon is used;

Fig. 3 is a side-elevation in the writing position;

Fig. 4 is a side-elevation during the act of introducing the auxiliary ribbons between the 20 papers to be written on; and

Fig. 5 shows a detail of a special design.

A rod 1, running longitudinally and parallel to the platen-carriage, is mounted onto the latter by means of holders 2 the form of which is 25

adapted to the model of typewriter at hand. A support consisting of two lateral parts 3 and a flat stiffening rib 4 can be plugged onto said rod 1, for which purpose the rear ends of lateral parts 3 are adapted as clamps. After having 30

thus mounted support 3—4 on rod 1, the first can be rotated about the latter. A shaft consisting of two rods 5 and 6, which latter are axially movable and guided inside a tube 7, is mounted in the front-ends of said lateral parts 3. 35

Said rods 5 and 6 are secured against a turning or revolving inside said tube 7 by a pair of keys 3 which engage in grooves 9 of said rods. The axial displacement of rods 5 and 6 is limited by the length of said grooves 9. A spring 10 is 40

arranged inside of tube 7 between rods 5 and 6 pushing the latter apart. At the exterior ends of members 5 and 6 there are two flat arms 11 curved in such a way as to be able to partly 45

envelop circumferentially the platen. The free ends of said arms 11 are provided with teeth 12 on their exterior sides. An auxiliary ribbon 13, the ends of which are held by end-pieces 14 provided with eyelets 15 for being hung onto said 50

teeth 12, is stretched between said arms 11. By reason of a plurality of teeth 12 being provided on both said arms 11 the auxiliary ribbon 13 may be attached to arms 11 in various positions, and it thus is possible to select for every model 55

of typewriter the most suitable position of the auxiliary ribbon 13.

Said two lateral parts 3 at their front-ends, into which the shaft consisting of rods 5 and 6 is mounted, possess at their interior sides curved surfaces 16 and rods 5 and 6 each possess a set-screw 17 lying upon curved faces 16. Shaft 5—6—7 with arms 11 being turned rearward the set-screws 17 move along curved faces 16 and are 10 being pushed against each other, and rods 5 and 6, overcoming the action of spring 10, move toward each other and thus slacken the auxiliary ribbon 13 hung onto arms 11, so that the latter may readily and easily be taken out and replaced 15 by a new one. As the auxiliary ribbon is held but on its end-pieces 14 which are not dyed, a soiling of one's hands is out of question. If we again turn shaft 5—6—7 with arms 11 forward, the auxiliary ribbon 13 automatically is 20 stretched and is subjected to the tension required for making good copies by way of spring 16 pushing apart rods 5 and 6.

The auxiliary ribbon 13, introduced between two copying papers, gives a copy of normal writing and another copy in a writing of opposite hand. If we use for the latter very thin and translucent paper, it may be as readily used as any other copy. The auxiliary ribbon 13, however, also may be covered on one side by a strip 30 of material impermeable to the copying dye, such as e. g. Cellophane, so that we obtain but one copy of normal writing.

Should several copies be made, we can use a second auxiliary ribbon 18, for which a support 35 consisting of two lateral parts 19 and a flat stiffening rib 20 is provided, which also—just like the device first described—carries a shaft of two parts with arms onto which this second auxiliary ribbon 18 is hung. The lateral parts 19 are of 40 such shape as to lie as flatly as possible, and they are provided with clamps 21 for mounting them onto rod 1.

Rod 1 by means of holders 2 is fastened once and for all to the platen-carriage of the typewriter. For using the device described, we first 45 mount the support with the first auxiliary ribbon 13 and afterwards, if so desired, also the support with the second auxiliary ribbon 18 onto rod 1. By reason of the fact that, first, the support is rotatively movable about rod 1, and, second, shaft 5—6—7 with arms 11 is rotatively mounted on 50 said support, an outstanding flexibility of the device is attained allowing us to readily and easily bring the auxiliary ribbon into its position of use, even when it must be brought underneath an oblique or curved sheet-holder. Due to this 55 property the device may be applied for all models of typewriters.

It is recommended to fix rod 1 immovably and 60 to adapt it at those places in which the clamps of the support are mounted with a flattening of its surface. Said clamps then are provided with a lower flat leg 22, whereas their upper leg 23 is bent to such a shape as to lie smoothly on rod 1. When the support then is mounted onto rod 1 and tilted forward the clamps themselves try 65 to rotate up to a point where their flat legs 22 come to lie onto the flattened places of rod 1. The supports thus are slightly pushed against

the drum and stopped in this position. The tendency of the support, when inserting the paper, of lifting itself away from the platen is thus eliminated.

I claim:

1. A device on typewriters for making copies by means of auxiliary ribbons consisting of a rod mounted on the platen-carriage of the typewriter, at least one support to be attached to said rod, a shaft revolvably mounted in lateral parts of said support, said shaft consisting of two parts joined and guided by a piece of tube containing a helical spring between the ends of said joined two parts, the latter being pushed away from each other under the action of said 15 spring, said axial displacement of said two parts being limited by keys inserted in said tube, the exterior ends of said shaft each possessing an arm curved corresponding to the circumferential curving of the platen, the free end of said arm 20 being adapted for supporting an auxiliary ribbon provided with end-pieces.

2. A device on typewriters for making copies by means of auxiliary ribbons, consisting of a rod mounted on the platen-carriage of the typewriter, at least one support to be attached to said rod, a shaft revolvably mounted in lateral parts of said support, said shaft consisting of two parts joined and held in line by a piece of tube containing a helical spring between the 25 ends of said two parts, the latter being axially displaceable within said tube, said displacement being limited by keys inserted in said tube, the exterior ends of said shaft each possessing an arm shaped according to the curvature of the 30 platen, means at the free end of said arm for supporting an auxiliary ribbon provided with end-pieces; and said lateral parts of said support being provided with curved faces, and the two ends of said joined shaft each carrying a set-screw which glides upon said curved faces when 35 rotating said shaft.

3. A device on typewriters for making copies by means of auxiliary ribbons, consisting of a rod mounted on the platen-carriage, at least one 45 support to be attached to said rod, a shaft revolvably mounted in lateral parts of said support, said shaft consisting of two parts joined and held in line by a piece of tube containing a helical spring between the ends of said two 50 parts, the latter being axially displaceable within said tube, said displacement being limited by keys inserted in said tube, the exterior ends of said shaft each possessing an arm shaped according to the curvature of the platen, means 55 at the free ends of said arms for supporting an auxiliary ribbon provided with end-pieces, said lateral parts of said support being each provided with a curved face, the two ends of said joined shaft each carrying a set-screw gliding upon 60 said curved face when rotating with said shaft, and clamps for mounting said support onto said rod, the lower legs of said clamps being flat and the upper ones being so curved in shape as to partly envelop said rod, said rod being further- 65 more flattened at those places where said clamps are mounted.

HANS ZIEGLER.
